UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

DESIGN FOR A LOCOMOTIVE HEADLIGHT.

Application filed June 8, 1923. Serial No. 6,446. Term of patent 14 years.

To all whom it may concern:

Be it known that I, NILS D. LEVIN, a citizen of the United States, residing at Columbus, in the county of Franklin and State of Ohio, have invented new, original, and ornamental Design for Locomotive Headlight, of which the following is a specification, reference being had to the accompanying drawing, forming part thereof.

Figure 1 is a perspective view in front elevation and Figure 2 is a perspective view in rear elevation.

I claim:

The ornamental design for a locomotive headlight substantially as shown.

In testimony whereof, I have hereunto set my hand.

NILS D. LEVIN.
